TYPEWRITING MACHINE

William A. Dobson, Wethersfield, Conn., assignor
to Underwood Elliott Fisher Company, New
York, N. Y., a corporation of Delaware

Application November 22, 1932, Serial No. 643,811

6 Claims. (Cl. 197—147)

This invention relates to means for securing quiet operation of typewriting machines.

In machines of the Underwood type, in which the type-bars swing up and back against a platen, the distance traveled by the heavy type-end of the bar is very great, necessitating high velocity, which becomes higher as the platen is approached, so that the noise of type-bar concussions is highly objectionable.

10 The type strikes against a work-sheet which is wrapped around a platen that is mounted upon a carriage, and the carriage must be stepped quickly between the rapid type-impressions. To permit speed, the carriage and platen have been 15 made relatively light, and the swift striking of the heavy type-bar against the light platen has proven to be a serious drawback.

It has been sought to overcome this objection by enclosing the typewriting machine in a sound-proof cabinet, but this has proven to be expensive.

20 Another means of minimizing the noise of operation has been to mount the types upon complicated movement-trains, which press the type against the paper, instead of causing it to strike, but this also has proven to be expensive.

25 It is sought by the present invention to type-write so quietly that the machine can be successfully used in offices where the usual typewriter noise would be unbearable, and to do so practically and inexpensively and without detracting from the simplicity of the machine. The invention is shown embodied in an Underwood portable typewriter, whose low cost is not appreciably enhanced by the present invention.

30 The organization of elements herein disclosed produces a successful machine of this class, which is being manufactured in large numbers for satisfied users.

35 The problem to which this invention is addressed, involves interdependent conditions, the chief of which is the necessity for speeding the type after it has once been started on its way to the platen. The start of the type is slowed, so as to render the key-touch easy; but the resultant loss of time has to be made up at a later stage of the type-bar stroke, so that the key will not have to dip too far. Moreover, the momentum of the operator's hand has to be absorbed to a great extent, the momentum being used in 40 increasing the speed of the type-bar, so that the finger may not be jarred at the conclusion of the down stroke of the key.

45 This particular one of the interdependent conditions, according to the present invention, is largely overcome by suddenly reducing the speed

5 of the type-bar, beginning at a point near the platen, there being provided for this purpose an elastic pad of high-grade rubber-packing, which is encountered by the type-bar when it is $\frac{3}{2}$ of an inch from the platen. Said packing yields, but is 10 resistant to the action of the type-bar, and slows the same to a degree at which, under usual conditions, it would deliver an under-strength impression upon the work-sheet, while the noise of the type-blow would still be considerably above 15 the maximum of auricular tolerance.

Another of the interdependent unfavorable conditions is the resonance of the platen. Its lightness causes it to augment the noise of concussion, even when the type-bar, being cushioned as 15 aforesaid, makes a weak impression as explained. This invention at this stage of the difficulty produces a two-fold result, namely, it reduces the sound to bearable limits, and also insures that the 20 weak blow of the type shall produce a bright and sharp impression upon the work-sheet.

To gain this double result in the described re-organization, the platen is made upon a weighted base consisting of a length of heavy-iron gas-pipe, upon which is vulcanized a cylinder of 25 heavily weighted soft rubber; and this is jacketed by wear-resisting rubber of medium hardness, that is, considerably softer than is usually employed for manifolding purposes. The great weight of the platen, due partly to its heavy- 30 metal core, and partly to the heavily weighted though soft-rubber cylinder thereon (covered by the jacket), is sufficient to enable the light type-blow to make an excellent, well-inked, clear impression upon the work-sheet; while the same 35 organization reduces the noise of the already-subdued blow to a point which is within the limit of tolerance to the ear. This is due to the co-operation of the described sound-subduing characteristics of the platen, with the aforesaid elastic rubber-packing against which the type-bar strikes. This packing serves as a sound-dampener, and the sound-subduing platen also serves as a sound-dampener. The sound-vibrations are 40 therefore controlled by the two sound-dampeners, 45 one of them contacting with the type-bar at its type-end, and the other being in contact at the same time with the type-bar at a point near its pivot.

The platen, although weighted, is within the 50 limit of weight which can be satisfactorily mounted upon the speeding typewriter-carriage.

The aforesaid organization is found in practice to offer a machine that is noticeably more silent than any machine heretofore developed in 55

the striking type-bar class, as distinguished from the type-pressing class.

Other features and advantages will herein-after appear.

5 In the accompanying drawing,

Figure 1 is a part-sectional elevation of a type-bar, segment, and paper-carriage of an Underwood portable typewriting machine provided with the present improvements; the parts being 10 shown in normal dimensions.

Figure 2 is a sectional perspective to illustrate the heavy-metal core of the platen, and the hollow head of the core.

15 Figure 3 is a sectional elevation of the platen, the type-bar, and the segment, showing the type printing upon a work-sheet.

Figure 4 is a sectional elevation, showing the usual type-action, and also showing the type-bar when it contacts with the resilient cushion when 20 the type is nearing the platen.

The usual type-keys 10 are mounted upon levers 11, fulcrumed at 12 and having pins 13 that work in slots 14 provided upon arms 15 of bell-crank 25 cranks 16, fulcrumed at 17. From the bell-crank 18 extend rearwardly links 19 to points 19 of pivotal connection with the type-bars 20, which are fulcrumed at 21 upon a segment 22, and carry types 23. The types strike rearwardly against a platen 24, around which is carried a work-sheet 25.

30 The slot 14 is inclined downwardly and rearwardly to the end that the leverage of the key 10 is made very great at the beginning of its down stroke, whereby the type-bar is started into action gently, thus securing an easy finger-touch.

35 As the key descends, the purchase of the lever 11 upon the bell-crank arm 15 is diminished, so that finally the type 23 is approaching the platen at high speed. This speeding up of the type-bar absorbs the momentum of the hand of the operator, so that the key eventually comes to rest without shock. This cushioning of the key-stroke at both beginning and conclusion is essential in 40 this class of machines.

45 The described increase in the velocity of the type-bar as it approaches the platen has been found to be detrimental, because the type strikes so sharply against the platen or paper as to produce a highly objectionable concussion.

An object of this invention is to minimize this 50 noise, or, at least, to overcome its objectionable sharpness, and to enable the type to not only print quietly, but also to make a black and clear impression upon the work-sheet. This result can be evolved by taking several steps in the 55 construction of the machine.

One step is to effect a substantial reduction in 60 the speed of the type as it strikes the paper, so that the impact of the type against the paper will be much reduced. The problem at this point involves the reduction of the speed by the use of 65 the herein-described means to a point at which the type delivers what would normally be an impression too weak to effect the necessary clearness in printing; it being premised that by under-speeding the type at the platen, it may, by taking still other steps, be rendered practicable to control the noise of the impact.

The checking of the speeding type-bar is effected by a yielding stop 26, which is a segment 70 of a rubber compound such as is generally made up for use as packing; this compound being flexible and resilient, and much more solid than a common soft-rubber band, and being substantially wear-proof, so that it is not cut by the 75 edges of the type-bars striking thereagainst.

This segment 26 is sunken between upper and lower ledges 27, 28, formed upon the front face of a metal segment-plate 29, which may be cast of aluminum or iron. The thickness of the packing is substantially $\frac{1}{8}$ of an inch, and the face of it is substantially $\frac{1}{16}$ of an inch wide. When the type-bar strikes the pad 26, the speeding type-bar is about $\frac{1}{8}$ or $\frac{3}{32}$ of an inch from the platen. The high resistance offered by the pad 26 checks the speed of the type-bar and type; the 10 type-bar sinking into the pad as seen at 30. Figure 3, and the speed of the type being suddenly very much reduced below normal, so that the type does not strike quite hard enough to make a satisfactory impression under ordinary 15 conditions.

The platen itself is one of the interdependent elements, the invention enabling the lightly-striking type-bar to produce a satisfactory clearly inked impression upon the work-sheet, and enabling this impression to be made by sound-subduing means.

20 For the platen there is used a wear-resisting cylindrical jacket 31, which may be made of the usual rubber compound. It is preferred to make 25 this compound from rubber, carbon-black, whiting, sulphur and zinc. The jacket has a density of 87 to 90, as determined by a densimeter. This jacket is supported by a heavily weighted soft-rubber core 32 of great bulk. This core is soft 30 and resilient and is made of a compound of rubber, magnesia, whiting, palm-oil, sulphur and paraffin, and has a density of 55 to 60.

25 This soft-rubber supporting body 32 is molded upon a core 33, which is a length of heavy-iron 35 gas-pipe, and is not only non-resonant, but also affords a rigid support for the cylindrical body 32 and the jacket 31 throughout their length. The body or cylinder 32 is molded upon the metal core, then ground to size; then cement is applied 40 to its periphery, and the jacket 31 is then forced upon said body. The jacket may also be poured in a mold around said body 32.

At Figure 1, the platen has the usual length, 45 some 10 inches. The diameter of the platen is 1 $\frac{1}{4}$ inches. For the purpose of the invention, it has been found that the following dimensions are 50 satisfactory for a platen 1 $\frac{1}{4}$ inches in diameter. The thickness of the wearing jacket 31 is $\frac{3}{32}$ of an inch. The thickness of the weighted soft-rubber core 32 is $\frac{1}{32}$ of an inch; its outside diameter being 1 $\frac{1}{16}$, and its central perforation being 55 about $\frac{3}{8}$. These proportions give proper weight to the axle 33 which may be $\frac{1}{8}$ inch pipe size having a bore of about $\frac{1}{2}$ of an inch, and to the cylindrical body 32 of the platen, and, by reason 60 of this weight of the platen, the slowly moving type is enabled to make a bright and clearly inked impression through the ribbon 34 upon the work-sheet 25; while the noise of the lightly-striking type is almost eliminated, by the co-operation of the soft sound-deadening core of the platen 24 with the resilient rubber-packing 26 into which the type-bar sinks. The platen is from 40 to 50 per cent. heavier than a standard regulation 65 platen of the same over-all dimensions. It will be seen that by this co-operation the vibration of the type-bar is subdued at two places, one place at 26 and the other where the type contacts with the sound-subduing platen.

70 The platen is mounted in end plates 35, 36 of a carriage by means of axle 37, 38, and is provided with a releasable line-space wheel 39. End-wise movement of a left-hand platen-knob 40 releases the platen from the control of the line- 75

space wheel. Normally, as at Figure 1, levers 41 act upon a plate 42 to clamp the line-space wheel against a disk 43, which is fixed upon a hollow stub-shaft 44. In the Figure 1 position, a cam 45, upon the axle 37, spreads apart the levers 41 and clamps 42 against the line-space wheel 39, holding the latter to the head-disk 43. The levers are mounted upon the head 44, which is slotted to receive the levers 41, and said head is fitted in a shell 46, which at one end extends within the platen and at the other end extends out from the platen, the shell being tapered at its inner end at 47 and rigidly secured upon a neck 48 formed upon the left-hand end of the tubular axle 33. The inner axle is flattened at 49, whereby it is splined to the tubular axle, a plug 50 having an oblong bore 51 fitting the spline 49, being fastened by screw 52 in the right-hand end of the hollow axle 33, as shown in pending application 548,863, filed July 6, 1931 (now Patent No. 1,931,064, dated Oct. 17, 1933). By releasing screws 52, 53, the platen may be detached from the platen-frame; the axle 38 being first withdrawn and then the axle 37 being pressed inwardly to clear it from the carriage-frame end 35.

When it is desired to set the machine for heavy manifolding, the platen may be adjusted forwardly at each end by means of device disclosed in Patent 1,870,001 granted to me. The carriage runs upon a track-frame 54 by means of a bearing-ball 55, and the track-frame is mounted upon upper and lower links 66 and 67, the upper link being formed in two parts which permit a relative endwise adjustment. An eccentric 68 is turned to lengthen or shorten the link 66, and then the device is fastened by a screw 66^a working in the eccentric 68. The links are connected at their forward ends at 69, 70 to the carriage-track frame 54, and at their rear ends are hinged at 71, 72, to the framework, and hence lengthening the links 66 will adjust the platen bodily forwardly and enable the types to print with sufficient force for manifolding.

The weighted soft-rubber cylinder 32 is preferably vulcanized to the iron pipe 33. At its end, the cylinder may have a counterbore to receive the cup 46, which may be riveted or welded upon the end of pipe 33. The head 44 fits into the outer end of the cup, and is secured thereto by a screw 73. The cup 46 serves as an enlargement of tube 33, and there is no metal connection between the wear-resisting jacket 31 and the carriage-frame; said jacket 31 being supported only by the soft-rubber cylinder, which is non-resonant, and the counterbore in the end of the rubber cylinder fitting the cup, which therefore yieldably supports the end of the rubber platen. This cup is mainly outside of the printing field of the platen and tapers at its inner portion, to afford room for sufficient of the soft-rubber cylinder 32 to serve the described purpose.

Variations may be resorted to within the scope of the invention, and portions of the improvements may be used without others.

Having thus described my invention, I claim:

1. A typewriter-platen having a wear-resisting jacket which is compounded of rubber, carbon-black, whiting, sulphur and zinc, and having a density of about 87 to 90, and filled by a weighted soft-rubber cylinder compounded of rubber, magnesia, whiting, palm-oil, sulphur and paraffin, and having a density of 55 to 60, and a metal core.

2. A typewriter-platen having a wear-resisting jacket which is compounded of rubber, car-

bon-black, whiting, sulphur and zinc, and having a density of about 87 to 90, and filled by a weighted soft-rubber cylinder compounded of rubber, magnesia, whiting, palm-oil, sulphur and paraffin, and having a density of 55 to 60, the platen being substantially of the following proportions: diameter of the platen 1 1/4 inches; thickness of the wearing jacket 3/2 of an inch; outside diameter of the soft-rubber cylinder 1 1/8 of an inch, and central perforation of the same about 3/8 of an inch in diameter; and a metal core.

3. A typewriter-platen having a wear-resisting jacket which is compounded of rubber, carbon-black, whiting, sulphur and zinc, and having a density of about 87 to 90, and filled by a weighted soft-rubber cylinder compounded of rubber, magnesia, whiting, palm-oil, sulphur and paraffin, and having a density of 55 to 60, the platen being substantially of the following proportions: diameter of the platen 1 1/4 inches; thickness of the wearing jacket 3/2 of an inch; outside diameter of the soft-rubber cylinder 1 1/8 of an inch, and central perforation of the same about 3/8 of an inch in diameter; and a metal core; said core being a soft-iron pipe having a bore 7/8 of an inch in diameter.

4. In a typewriting machine, the combination with a set of key-operated type-bars, of means for suddenly decreasing the speed of the type-bar beginning when the type is close to the platen, said means being in the form of an elastic pad of high-grade rubber-packing which is struck by the type-bar, slowing the type-bar sufficiently to minimize the concussion of the type upon the work-sheet, and a cylindrical platen which is overweighted so as to enable the weakly striking type-bar to effect a clear and sharp impression upon the work-sheet; the platen being mainly a substantially solid cylinder of weighted soft rubber which is jacketed with a thin wear-resisting cylinder, the soft interior of the platen serving to muffle the sound of the type-blow, and the soft-rubber platen-body co-operating with the soft-rubber type-bar stop to dampen the type-bar vibrations both at its free end and at a point near the type-bar pivot, said wear-resisting jacket being a compound of rubber, carbon-black, whiting, sulphur and zinc, and having a density of about 87 to 90, and said weighted soft-rubber cylinder being a compound of rubber, magnesia, whiting, palm-oil, sulphur and paraffin, and having a density of 55 to 60.

5. In a typewriting machine, the combination with a set of key-operated type-bars, of means for suddenly decreasing the speed of the type-bar beginning when the type is closed to the platen, said means being in the form of an elastic pad of high-grade rubber-packing which is struck by the type-bar, slowing the type-bar sufficiently to minimize the concussion of the type upon the work-sheet, and a cylindrical platen which is overweighted so as to enable the weakly striking type-bar to effect a clear and sharp impression upon the work-sheet; the platen being mainly a substantially solid cylinder of weighted soft rubber which is jacketed with a thin wear-resisting cylinder, the soft interior of the platen serving to muffle the sound of the type-blow, and the soft-rubber platen-body co-operating with the soft-rubber type-bar stop to dampen the type-bar vibrations both at its free end and at a point near the type-bar pivot, said wear-resisting jacket being a compound of rubber, carbon-black, whiting, sulphur and zinc, and

- having a density of about 87 to 90, and said weighted soft-rubber cylinder being a compound of rubber, magnesia, whiting, palm-oil, sulphur and paraffin, and having a density of 55 to 60; the part being of the following proportions: diameter of the platen $1\frac{1}{4}$ inches; thickness of the wearing jacket $\frac{3}{2}$ of an inch; and the thickness of the wall of the soft-rubber cylinder $\frac{1}{2}$ of an inch.
- 5 6. A typewriter-platen having a wear-resisting jacket which is compounded of rubber, carbon-black, whiting, sulphur and zinc, and having a density of about 87 to 90, and filled by a weighted soft-rubber cylinder compounded of rubber,
- 10 magnesia, whiting, palm-oil, sulphur and paraffin, and having a density of 55 to 60, the platen being substantially of the following proportions: diameter of the platen $1\frac{1}{4}$ inches; thickness of the wearing jacket $\frac{3}{2}$ of an inch; outside diameter of the soft-rubber cylinder $1\frac{1}{8}$ of an inch, and central perforation of the same about $\frac{3}{8}$ of an inch in diameter; and a metal core; said cylinder being mounted upon a soft-iron pipe having a bore of $\frac{3}{2}$ of an inch diameter, expanded at one end to form a hollow head for containing a platen-releasing mechanism.

WILLIAM A. DOBSON.
